Primary Examiner — Nathan M Johnston

(57) **CLAIM**

The ornamental design for a foldable bathtub tray as shown and described.

DESCRIPTION

FIG. 1 is a top, front and right side perspective view of a foldable bathtub tray showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 2;

FIG. 10 is a top, front and right side perspective view showing the foldable bathtub tray in a folded state; and, FIG. 11 is a top, front and right side perspective view showing the foldable bathtub tray in a state of use.

The broken lines in the drawings illustrate portions of the foldable bathtub tray which form no part of the claimed design.

The unevenly dashed broken lines illustrate the boundary of the enlarged views and form no part of the claimed design.

1 Claim, 11 Drawing Sheets
